UNITED STATES PATENT OFFICE.

CARL P. BROCKWAY, OF TOLEDO, OHIO, ASSIGNOR TO INDUSTRIAL RESEARCH CORPORATION, OF TOLEDO, OHIO, A CORPORATION OF DELAWARE.

MOTOR-DRIVE.

1,352,112.

Specification of Letters Patent. Patented Sept. 7, 1920.

Application filed February 14, 1919. Serial No. 276,950.

To all whom it may concern:

Be it known that I, CARL P. BROCKWAY, a citizen of the United States, residing at Toledo, in the county of Lucas and State of Ohio, have invented certain new and useful Improvements in Motor-Drives, of which I declare the following to be a full, clear, and exact description.

This invention relates to improvements in gearing for use particularly in starting internal combustion engines.

One object of the invention is the provision of means whereby the jerky motion of the engine fly-wheel may be absorbed by a compression spring.

Another object of the invention is the provision of means whereby the jerk absorbing mechanism may be entirely inclosed in order that the same may be immersed in oil and 20 also to muffle any noise that may be incident to the operation of the mechanism.

Other objects, and objects relating to details of construction and economies of manufacture, will appear as I proceed with the 25 description of that embodiment of the invention, which for the purposes of present application, I have illustrated in the accompanying drawing, in which:

Figure I is a view partly in section and 30 partly in side elevation of a starting gearing embodying my invention.

Fig. II is a view similar to Fig. I, but with the starting gearing in mesh with the engine fly-wheel.

Fig. III is a cross section taken on the line III—III Fig. I.

Similar reference characters refer to similar parts throughout the views.

My invention is intended primarily for 40 use in that class of gas engine starters, in which the power for turning the engine fly-wheel comes from an electric motor, and I have indicated a fragment of such a motor at 10 in the drawing. The motor shaft 11 45 protrudes some distance from the end of the motor, and in the embodiment of the invention illustrated, is unsupported except by the motor bearings. Just outside the motor a collar 9 is fixed to the shaft. The latter at 50 about midway of its exposed portion is squared for a distance, as at 12, to provide for longitudinal movement thereon of a sleeve 13 which has a correspondingly formed

opening therethrough, the dimensions being such as to produce a loose sliding fit.

Beyond the squared portion 12 of the shaft the latter is turned down to form a portion 14 which is of still smaller circular cross section. It carries a compression spring 15, bearing at one end against a washer 16, which rests against the adjacent end of the sleeve 13. The opposite end of the spring bears against a cup shaped washer 17, resting against the collar 18, which is movable along the shaft in order to adjust the tension of the spring, said movement being effected by means of a nut 19, threaded upon the end of the shaft and locked in any one of various positions by means of a locknut 20, which, if desired, may be held in place by a cotter 70 pin 21 penetrating registering holes in the nut and shaft.

The sleeve 13 is exteriorly threaded as shown in the drawing to fit the correspondingly threaded interior surface of a cylinder 22, which carries on its forward end a drive wheel 23, preferably a pinion adapted to mesh with teeth 24 on a fly-wheel 25 of an internal combustion engine. In order to produce a tendency in the cylinder and pinion 80 against motion of rotation I may secure to the cylinder or to the pinion a disk 26 upon one half of the rim of which is a semi-annular weight 27.

The forward end of the cylinder 22 carries 85 a packing ring 28 in which is located packing 29 forming a bearing for the cylinder on the shaft. The joint between the cylinder and the ring 28 should be oil tight. In an embodiment of the invention such as 90 shown in the drawing where the outer end of the motor shaft is unsupported, I prefer to close the outer extremity of the cylinder by means of a screw cap 30, packing 31 being interposed between the cylinder and cap if 95 necessary to make the joint oil tight. The collar 18 is of a size to provide a smooth sliding fit with the smooth interior wall of the outer end of the cylinder, one or more openings or grooves 32 through the collar 100 providing a passage for oil as the parts move back and forth longitudinally. Other openings or grooves 33 (Fig. III) are formed in the sleeve 13 for a similar purpose.

Assuming that the engine with which my 105 invention is employed is not running, and

that it is desired to start the same, and assuming that the starting gearing is in the position illustrated at Fig. I, the motor 10 is set in operation, turning the shaft 11 in 5 the direction of the arrow A, Fig. I.

The sleeve 13 turns with the shaft because of the squared connection between the two parts. The cylinder 22 however, because of the weight 27, possesses a tendency against 10 rotation. Consequently it remains in the upright position illustrated in the drawing and is moved forward toward the motor by the action of the screw threaded sleeve 13 upon its own interiorly screw threaded 15 face. During this forward movement, teeth on the pinion 23 mesh with some of the fly-wheel teeth 24. There is no tendency to turn the fly-wheel however, until the longitudinal movement of the cylinder is stopped by the 20 collar 9. Then, although the forward movement of the cylinder is interrupted, there is still possible a relative motion between the cylinder and sleeve because of the fact that the sleeve may move outward upon the shaft. 25 Such motion is opposed by the spring 15, and if there were no inertia in the fly-wheel to be overcome, it would not take place, but the cylinder would turn with the sleeve to rotate the fly-wheel. However, due to the 30 weight of the fly-wheel and the friction in the engine as well as the compression in its cylinders, the inertia of the fly-wheel offers a resistance to rotation which is greater than the resistance of the spring 15 against compression. Accordingly, further rotation of 35 the shaft forces the sleeve 13 back against the resistance of the spring until that resistance becomes greater than the resistance of the fly-wheel, after which the cylinder turns 40 and rotates the fly-wheel.

While the engine is being turned over by the starting motor the rotation of the fly-wheel is irregular or jerky, because it is slowed up by the compression strokes of 45 the pistons in the various cylinders, and receives a sudden forward impulse each time that a piston starts down after a compression stroke. In my construction, whenever there is a retardation of the rotation of the 50 fly-wheel, the added resistance to rotation, transmitted to cylinder 22 from the fly-wheel, causes the sleeve 13 to move outward, compressing the spring 15 and storing up energy therein. When that particular compression stroke is completed, the energy thus 55 stored up in the spring is expended, moving the sleeve forward again, thereby adding slightly for a brief instant to the speed of rotation of the cylinder over that which is 60 produced by the rotation of the motor shaft.

In this way, the jerks in the rotation of the fly-wheel are absorbed by the spring 15 and the load upon the motor is rendered fairly constant.

When the engine begins firing, the rotation of the fly-wheel is greatly and suddenly accelerated, causing the cylinder 22 to rotate at a speed much greater than that of the motor shaft and the sleeve 13, whereupon relative motion between the sleeve 13 and 65 cylinder 22 must take place, and accordingly the cylinder 22 moves rapidly backward from its position of Fig. II to that of Fig. I.

I am aware that the particular embodiment of my invention above described, and illustrated in the accompanying drawing, is susceptible of considerable variation without departing from the spirit thereof, and therefore I desire to claim my invention 70 broadly as well as specifically as indicated by the appended claims.

I claim as my invention:

1. In combination with a motor driven shaft having a free extremity, a cylinder 75 mounted upon said shaft, means within the cylinder operatively connected with the shaft for imparting a limited longitudinal movement to said cylinder, said means at the termination of said longitudinal movement locking the shaft and cylinder together 80 rotatably, said cylinder being closed at its outer end and having an oil tight bearing upon the shaft at its inner end, and a driving wheel mounted upon said cylinder. 85

2. In combination with an engine fly-wheel, a motor driven shaft, a sleeve mounted upon said shaft non-rotatably but capable of a slight longitudinal movement with respect thereto, a cylinder surrounding said 90 sleeve and shaft closed at one end and having a screw thread connection with said sleeve, a pinion fixed to the other end of said cylinder and adapted to drive said fly-wheel, and resilient means for limiting the longitudinal movement of said sleeve. 100

3. In combination with a motor driven shaft having a free extremity, a sleeve mounted upon said shaft non-rotatably, a cylinder surrounding said sleeve and shaft 110 and having a screw threaded connection with said sleeve, a drive wheel fixed to said cylinder, said cylinder being inclosed at its outer end and having an oil tight bearing on the shaft at its inner end, said sleeve being 115 provided with an oil passage extending longitudinally therethrough.

In testimony whereof, I affix my signature.

CARL P. BROCKWAY.
